UNITED STATES PATENT OFFICE.

JOSEPH L. DAVIS, OF ABBINGDON, ILLINOIS.

EGG TURNER FOR INCUBATORS.

Application filed February 10, 1925. Serial No. 3,281.

To all whom it may concern:

Be it known that I, JOSEPH L. DAVIS, a citizen of the United States, residing at Abingdon, in the county of Knox and State of Illinois, have invented certain new and useful Improvements in Egg Turners for Incubators, of which the following is a specification, reference being had to the accompanying drawings.

10 This invention relates to egg turners for incubators and more particularly to an attachment for that type of incubator employing a plurality of units of superposed pivotally supported trays, the trays of each unit being connected together for simultaneous movement.

An important object of the invention is to provide a construction operable from the exterior of the incubator for simultaneously shifting all of the units to change the angle of the trays thereof and in which the number of operating parts is reduced to a minimum.

25 A further and more specific object of the invention is to provide a novel and improved windlass shaft mounting for operating the control elements for imparting movement to said units.

30 A further object of the invention is to provide a device of this character which is readily adjustable to compensate for wear of the parts or changes in relative size of the parts due to the changes of temperature to which an instrument of this character is subjected.

These and other objects I attain by the construction shown in the accompanying drawings, wherein for the purpose of illustration is shown a preferred embodiment of 40 my invention and wherein:

45 Figure 1 is a partial sectional view taken through an incubator having egg turning apparatus constructed in accordance with my invention;

Figure 2 is an enlarged detailed sectional view showing the connections between the windlass shaft and operating mechanism;

50 Figure 3 is a section on the line 3—3 of Figure 2;

55 Figure 4 is a detailed sectional view showing the mounting of one of the wheels and flexible elements upon the shaft;

Figure 5 is a perspective of the connection employed between adjacent units;

Figure 6 is a detailed sectional view 65 through one of the hangers;

Figure 7 is a perspective of one of the end bearings of the shaft; and

Figure 8 is a perspective view of the other 60 of the end bearings.

Referring now more particularly to the drawings, the type of incubator in which my invention is intended for use includes a plurality of egg tray units 10, each including a plurality of vertically superposed 65 trays 11 pivotally connected at the corners thereof to vertically extending links 12, the upper ends of these links being connected to centrally pivoted supports 13 so that by grasping any link or tray of the unit, the 70 entire group of trays in the unit may be simultaneously tilted or inclined thereby effect a turning of the egg. Structures of this character are old and well known and are accordingly not claimed by me as a part 75 of my invention except in combination with the structure hereinafter set forth. These incubators have the units 11 arranged in rows extending longitudinally of the incubator and between opposed end walls 14. 80

In accordance with my invention, I provide the end walls 14 above and in approximate alignment with the side of one row of units 10 with opposed bearings 15 and 16. The bearing 16 is in the form of a plate 17 85 bolted to the wall 14 with which it coacts and having in its inner face a socket 18 for the reception of one end of a shaft 19. The bearing 18 is in the form of a plate 20 having extending outwardly therefrom a U-shaped ledge 21 between the arms of which and upon the base of which the opposite end of the shaft is adapted to rest, this end of the shaft being removable through the open top of this support. Intermediate the 90 end walls 14, the top 22 of the incubator has secured thereto hangers 23 each in the form of a hook having its opening 24 directed upwardly and to one side and upon its bight portion a depending extension 25 having a 100 threaded bore 26. The upper end of this bore is enlarged, as at 27, for the reception of T-stems 28 formed upon sleeves 29 rotatably receiving the shaft. Through the

threaded portion 26 of the bore, a set screw 30 is directed for adjusting the sleeves vertically so that the shaft may be properly aligned. It will be obvious that a shaft 5 supported as described may be readily removed to permit free access to all parts of the incubator for the cleaning to which these incubators must be subjected between hatchets.

10 This shaft has secured thereto at spaced intervals wheels 31, these wheels corresponding in number and arrangement to the spaces between adjacent faces of units and the spaces between the outermost units and the 15 adjacent walls of the incubator and being arranged approximately centrally of such spaces. At one end, the shaft has secured thereto a sprocket wheel 32. Upon the end wall at an opening formed in the wall, a 20 plate 33 is secured to the outer surface of the wall, this plate having an extension 34 passing through the opening to the interior of the incubator. The plate and its extension have a bore 35, the inner end of which 25 is reduced, as at 36, to form a bearing for a shaft 37, which shaft has a collar 38 abutting the shoulder formed by the reduction of the bore and outwardly of this collar has a squared wrench receiving portion for co-action with a wrench 40. Secured to the inner wall of the incubator in alignment with the shaft is a plate 41 having an opening through which the shaft passes and a pair of arms 42 rigidly supporting a bearing 43, 30 through which the inner end of the shaft is directed. At the inner end of the bearing, a cotter pin 44 is passed through the shaft and coacts with the collar 38 to hold the shaft against longitudinal shifting. Upon 35 the shaft intermediate the plate 41 and bearing 43, a sprocket wheel 45 is mounted which is connected by a chain 46 with the sprocket wheel 32 so that upon rotation of the shaft 37, the shaft 19 is correspondingly rotated.

40 Secured to the links 12 of the units 10 at the side of the units below the shaft and arranged in approximate alignment with one another is a plurality of bars 47 one for each unit, each bar 47 being pivotally engaged with the links of its associated unit and at the side of the unit above mentioned. The ends of these bars are preferably upturned, as indicated at 48, and extend into proximity to one another. Secured to each 45 wheel 31 is a cable 49 adjustable as to length by means of a turn buckle 50. The cables of the endmost wheels 31 are connected at their lower ends to the outer ends of the bars 47 of the outermost units 10. The 50 flexible elements 49 preferably each have the turn buckle thereof arranged at the lower end thereof. Each of the opposed ends of the bars 47 has attached thereto a pivotally connected link 51 having an eye 51^a receiving a hook 50^a formed upon the lower end

of the lower member of the turn buckle. The outer ends of the outermost bars 47 have eyes 48 receiving similar hooks formed upon the lower ends of the lower members of their associated turn buckles.

After the shaft has been properly placed, the cables are attached and tightened by means of the turn buckle so that an equal tension is placed upon the units. It will, of course, be seen that by rotating the handle, 75 the shaft 19 will be rotated and since the cables of alternate wheels 31 are connected to the wheels at opposite sides thereof, one end of each of the bars 47 will be elevated 80 while the opposite end thereof is permitted to depress, causing a corresponding movement of the links of the unit and accordingly of the trays of the unit. Attention is further directed to the fact that by the construction hereinbefore illustrated, the 85 number of flexible elements employed is reduced to a minimum and accordingly the number of connections and the like which must be made in installing the device is materially reduced. Attention is directed to 90 the fact that by a structure of this character, turning of the eggs within the incubator can be accomplished without opening the incubator, therefore, preventing the loss of heat occasioned by opening of the 95 doors of the machine during the period when the trays are being shifted. Furthermore, by an apparatus of this sort on an ordinary type of machine, a procedure ordinarily requiring thirty-four operations is accomplished by a single operation. Since the 100 construction hereinbefore set forth is obviously capable of a certain range of change and modification without in any manner departing from the spirit of my invention, I do not limit myself to such specific structure except as hereinafter claimed.

I claim:—

1. In combination with an incubator having a plurality of units of superposed pivotally supported trays therein, a windlass disposed longitudinally of the incubator and arranged within the same, connections between adjacent sides of adjacent units whereby the adjacent sides may be moved in unison and connections between said connections and the windlass for moving alternate connections between units in opposite directions.

2. In combination with an incubator having a plurality of units of superposed pivotally supported trays therein, the trays of each unit being connected at their side edges by vertically extending bars, a horizontal bar connecting the vertically extending bars of each unit and pivotally engaged with each thereof, connections between adjacent ends of adjacent horizontal bars whereby they may be caused to move in unison, a windlass, and connections between said con- 120 125 130

nections and the windlass for moving alternate connections between units in opposite directions.

3. In combination with an incubator having a plurality of units of superposed pivotally supported trays therein, the trays of each unit being connected at their side edges by vertically extending bars, a horizontal bar connecting the vertically extending bars of each unit and pivotally engaged with each thereof, connections between adjacent ends of adjacent horizontal bars whereby they may be caused to move in unison, a windlass, connections between said connections and the windlass for moving alternate connections between units in opposite directions, said connections between bars including a link pivoted to each end of each bar, the connections between the windlass and

a flexible element having at its lower end a turnbuckle, the turnbuckle including a hook engaged in eyes formed upon the free ends of the links at the adjacent ends of the horizontal bars.

4. In combination with an incubator having a plurality of units of superposed pivotally supported trays therein, each unit being supported from its upper end, a windlass disposed longitudinally of the incubator and arranged within the same above the units, connections between adjacent sides of adjacent units whereby the adjacent sides may be caused to move in unison and connections between said connections and the windlass for moving alternate connections between units in opposite directions.

In testimony whereof I hereunto affix my signature.

JOSEPH L. DAVIS.
